GAS BURNER

Philip J. Sonner, Winfield, Kans.

Application March 16, 1935, Serial No. 11,421

2 Claims. (Cl. 158—106)

My improvement comprises a gas burner designed to meet the demand for a burner that will operate satisfactorily on either 1000 B. t. u. natural gas or 1000 B. t. u. substitute gas without changing the adjustments on the burner; and further, a burner that will operate satisfactorily on the various low B. t. u. manufactured gases.

In the design of a burner of this character a number of very definite problems arise, all of which have been carefully considered and provided for in the present invention.

Flashback must be overcome, this I have successfully accomplished by increasing the depth of the burning ports and by making them as narrow as shop practice would permit. However, the deep narrow ports occasion considerable resistance to the flow of gas and it is therefore desirable to make the sides of the ports smooth and free from rough projections. The narrow slotted ports, however, prevent the flame from traveling back down through them, which sets up a definite resistance to flashback.

The additional depth of the burning ports by increasing the area of metallic surface contacted by the air-gas mixture during its flow from the orifice to the burning edge, presented the possibility of heating the air gas mixture to such an extent that excessive pressures would result within the burner box. I overcome this tendency by cooling the burner head, this is done by bringing the secondary air for combustion up between the ports; this feature also furnishes a further advantage in that it gives a desirable distribution of such secondary air throughout the entire fire.

To recapitulate; my improved gas burner includes an increased area of cooling surface on the burner head for the purpose of reducing the heating effect at these points; next, the increased depth of port overcomes flashback under variable conditions; and finally, I provide a wide and improved secondary air distribution to the fire. These and other advantages will be apparent from a study of the drawing and as amplified through the description thereof which follows.

Fig. 1 is an end view of a single burner; it being understood my burner may be employed in multiple units if so desired. Fig. 2 is a side elevation of the burner shown in Fig. 1; a portion of the figure is broken away for purposes of description. Fig. 3 is a plan view of the burner. Fig. 4 is an end view of a modified form of the burner. Fig. 5 is a side elevation of the burner shown in Fig. 4. Fig. 6 is a top view of the elements seen in Fig. 2 with the burner port section disclosed in Fig. 3 removed from the assemblage. Similarly Fig. 7

shows a top view of the elements seen in Fig. 2 after removing the parts seen in Figs. 3 and 6. Similarly Fig. 8 shows a top view of the base section seen in Figures 1 and 2 after removing the parts disclosed in Figures 3, 6, and 7. Fig. 9 represents a view in section as taken along the line IX—IX in Fig. 2, and looking in the direction of the arrows. Fig. 10 shows a fragmentary sectional view of the burner port as taken along the line X—X in Figure 2, and looking in the direction 10 of the arrows. Fig. 11 is a sectional view as taken along the line XI—XI in Fig. 1 and looking in the direction of the arrows. Fig. 12 is a sectional view as taken along the line XII—XII in Figure 4, and looking in the direction of the arrows. Fig. 13 is a plan view of the burner base plate and Venturi tube integral therewith. Similar numerals of reference designate the same part throughout the several figures of the drawing.

Referring to the drawing, at 10 are the base casting walls, integral with an intermediate cast T-pipe fitting 11 provided with a jet 12. A rectangular shaped upper portion 13 is also integral with the side walls 10 and at the four corners thereof may be seen corner elements 14 and a raised triangular portion 15. Upon the base seen in Fig. 8 and just described, I next assemble the element seen in Fig. 7 which has a base member 16 as a plate supported by the four corner elements 15. Integral with the member 16 is a Venturi tube 17 extending a little below the base 16 as at 17x and upwardly the height desired as seen in Figs. 9, 11, and 12. This Venturi tube may be surrounded by the wall element 18 as shown Figures 1, 2, and 11 in which case a slotted projection 19 would occur at the upper part of the end walls for purposes later explained. I next assemble an inner box-like element 20, open at its lower end and surrounding the Venturi tube 17 as disclosed in Figs. 6, 9, 11, and 12. The lower end of the element 20 is provided with a pair of centrally disposed extensions 21 and a pair of centrally disposed extensions 22, thus providing ports 23 and 24 at the lower side and end walls of the element through which the air-gas mixture, admitted through the jet 12, tube 17 and passage 25, will pass into the passage 26 intermediate the element 20 and the outer side walls 18. It will be noted that the upper end of the element 20 is closed by an inverted V-shaped roof portion 50 as seen at 27.

The assemblage shown in Figures 1 and 7 just described is now ready to receive the burner element seen in Fig. 3. As will be noted in Figs. 4, 5, and 12, this element may have a depending

box like side wall section cast integral with the burner section as at 18x with slotted projections such as 19x adapted to register with the slotted projection 16x, Fig. 13, and be clamped by the bolt 5 means 28. Or the burner element may fit as seen in Figs. 1, 2, 9, 10, and 11 upon the upper part of the wall element 18 and slotted projections 19' register with the projections 19 for bolt clamping purposes; the passage 26 leading to the burner 10 ports being the same in either application. If desired a gasket may be employed as seen at 29 or at 29'.

The burner seen in Fig. 3 and in the end views 15 Figs. 1 and 4 is flat on the top edge at 30, the sides extending downwardly for a distance as seen at 31 from which they curve inwardly and downwardly as at 32 to then flare outwardly along the line 33. The ends of the burner are preferably of the shape indicated at 18y. The effect of 20 the pitch given at 33 is shown in Figures 9, 10, 11, and 12 as a top section arranged above the roof element 21 previously described, and for a continuation of the gas passage 26 as seen at 26x admitting the air gas mixture to the gas ports as 25 later described. It will be noted in the several figures that the effect of the conventional Venturi tube seen at 17 is continued throughout the passage 25, the passage 26 and 26x, the wall elements being so fashioned or cast as to give this characteristic. Deep narrow slots 34 provide the gas 30 ports. A plurality of burner sections such as 35 are seen in Figures 2, 3, 5, 11, and 12 cast integral with the part 33 as disclosed in Fig. 11, in each of the sections 35 is disclosed the deep narrow slotted orifices 34. Wide air passages for secondary air therefore occur from the side 36 to the side 37 as clearly shown in Figs. 2 and 9. The effect of this secondary air upon the flame at the 35 burner tip 30 is very pronounced both for cooling the members 35 as well as for improving the secondary air distribution.

My burner by eliminating flashback also eliminates noise and fire hazards and other dangers. The invention in general is for similar purposes to that of my pending application for Gas burners, Serial No. 693,128.

Such modifications may be employed as lie within the scope of the appended claims. Having fully described my invention, what I now claim as new and desire to secure by Letters Patent is:

1. In a gas burner, a supporting member having a gas service therein including a jet vertically disposed; a base member arranged upon the supporting member including a Venturi tube passing through said plate and extending more above 15 than below the plate in gas receiving relationship to said jet; a box-like enclosure surrounding said tube and defining a passage therebetween, and having an inverted V-shaped top portion and gas ports adjacent said plate, a flat top gas burner 20 element arranged above the top portion of the box-like enclosure and provided with a corresponding inverted V-shaped under portion to define a selected passage communicating with said first passage through said gas ports; an outer 25 housing element extending from said plate and supporting said burner element; rectangular burner sections for the burner element spaced apart and in parallelism and having air passages 30 therebetween from side to side of said burner element and downwardly extending along the sides thereof externally of said inverted V-shaped under portion; said rectangular burner section having a narrow vertical rectangular slot of considerable depth communicating with said selected 35 passage.

2. A gas burner as defined in claim 1, characterized by the further fact that the circuitous passages leading from the Venturi tube to the burner have Venturi tube characteristics. 40

PHILIP J. SONNER.
